CLOSURE SECURING MEANS

Application filed July 10, 1930. Serial No. 467,007.

This invention relates to improvements in fastening means for hub caps, tank fillers and the like.

One of the objects of the invention is to provide a simple and effective latching means, more especially means such as can be arranged in the cap itself without the addition of extra parts.

In the accompanying drawing:

Fig. 1 is a front elevation of a wire wheel hub cap having the improved features incorporated therein.

Fig. 2 is a side elevation of the same.

Fig. 3 is a fragmentary section taken on an axial line of a portion of an assembled hub cap and hub, showing the method of latching employed.

Fig. 4 is a modification, it being an illustration of the manner in which the invention is applied to tank filler caps.

Referring to the drawing, 1 is a hub cap and 2 the integrally formed skirt thereof. In Fig. 3 the cap is shown in place in the hub 3 of a wheel, the means for latching the cap in place being a plurality of formed tongues 4 which are integral parts of the skirt 2. To form these tongues, the metal of the skirt is cut away or eliminated at suitable intervals to provide elongated openings, that portion of the skirt between each opening and the free edge of the skirt forming a bar 2', with a tongue 4 projecting from the inner edge thereof across the opening.

In forming the tongue, attention is given to the thickness of the material in the hub, as it is desired that the cap shall remain in place firmly and not be a source of noise. Therefore, referring to the character 8 as being the base of the tongue, in Fig. 3, it is seen that an upward bend, to provide a hump 9, is given the tongue, while the end 7 is given a downward bend at the proper distance from the annular flange 10 of the cap. The radial distance to the extremities of the humps is somewhat less than the diameter of the bore of the inturned flange 12 of the hub, so that in forcing the cap to its place, each of the tongues must be sprung inwardly sufficiently to pass the edges of the flange 12, while the slope of the portions

of the tongues between the end 7 and the hump 9 is such as to preclude any loosening during operation.

During the act of inserting the cap in place, the metal in the bars 2', connecting the base of the tongue with the main body of the skirt, undergoes a torsional stress, and allows the hump to pass through the flange, after which the spring tendency provides an efficient latching means. In order to remove the cap from the hub, it is only necessary to insert the blade of a screw driver or similar instrument between the flange of the hub and the cap and pry the cap from the hub.

The construction of the modified form of cap is similar to that shown in Figs. 1, 2 and 3. As this represents a tank filler cap or radiator cap, where leakage of the fluid might occur, a gasket 13 is interposed between the cap and neck 14, while the flange 15 of the cap is increased to provide an efficient grip for the hand. The annular skirt or flange is indicated at 16 and the spring tongue at 17.

Having thus described my invention, I claim:

1. The combination, with a member to be closed, of a closure for said member comprising a skirt thereon adapted to fit into said member, and a series of spring tongues each formed integrally with one wall of an apertured portion of said skirt and extending across said apertured portion, said apertured portion being of larger area than the area of the tongue to provide an open space on each side thereof, said tongue being adapted to yieldably engage said member to hold said closure in position.

2. The combination, with a member to be closed having an annular inturned flange, of a closure for said member comprising an annular skirt thereon adapted to fit into said flange, said skirt at a plurality of places being cut away to form at each place an elongated open space bounded by a weakened bar at the free edge of the skirt, and a spring tongue integrally formed with an intermediate portion of said bar and projecting across the open space, said open space being

of larger area than the tongue so as to extend beyond the sides thereof, each tongue being provided with a hump to yieldably engage said flange when said closure is inserted.

⁵ In testimony whereof, I have hereunto set my hand this 20th day of June, 1930.

EDWARD H. WITTENBERG.
